CONTAINER, ATOMIZER AND ADAPTER
SPRAYING DEVICE

William Moonan, Shaker Heights, and Vernon C. Groth,
Mentor, Ohio, assignors to Sprayon Products, Inc., Bed-
ford Heights, Ohio, a corporation of Ohio
Filed Apr. 8, 1963, Ser. No. 271,078
12 Claims. (Cl. 239—394)

This invention relates to liquid spraying devices and more particularly to atomizers adapted to spray medicaments and other liquid materials by means of a liquified propellant gas carried within a container separate from the atomizer.

Physicians and dentists find it convenient and desirable to apply medications of various types by means of atomizers. Dentists conventionally have compressed air supplies in their offices and selectively connect an atomizer containing the desired medicament to the compressed air hose. This provides a convenient and safe way of applying medications, but physicians frequently do not have compressed air supplies in their offices and many treatments must be given in the patient's home or in other locations where there is no compressed air supply. This fact has limited the use of sprays and atomizers because hand-operated atomizers are less effective and more difficult to use than atomizers operated by compressed air.

Accordingly, a general object of the present invention is to provide a device whereby atomizers can be powered by a liquified propellant gas contained in a container separate from the atomizer, whereby substantially the effectiveness and convenience of atomizers powered by compressed air can be obtained without the limitations inherent in the use of compressed air atomizers. Another object is to provide a simple and effective adapter for supporting a conventional, professional type atomizer of the sort used by dentists and physicians and connecting the atomizer to a container of liquified propellant gas, the container also being of a conventional type.

Other objects and advantages of the invention will become apparent from the following description of a preferred form thereof, reference being made to the accompanying drawings in which:

FIGURE 1 is a side elevation showing a conventional atomizer connected to a can containing a liquified propellant gas by an adapter made according to the present invention;

FIGURE 2 is a plan view of the assembly shown in FIGURE 1;

FIGURE 3 is a vertical sectional view taken along line 3—3 of FIGURE 2;

FIGURE 4 is a perspective showing the underside of the adapter of FIGURES 1, 2 and 3; and

FIGURE 5 is a perspective illustrating the adapter mounted on a propellant can, with the propellant can supported on a supporting base or plate.

As shown in FIGURES 1, 2 and 3, the present invention is especially adapted to atomizers of a well-known type that are extensively used by those physicians and dentists who have supplies of compressed air available in their offices. Such an atomizer is indicated in general at 10 in the drawings and comprises a typically tall and narrow glass reservoir 11 that is screwed into a metal atomizer body 12. A glass diptube 14 extends downwardly from the body 12 into close proximity to the bottom of the reservoir 11. The body 12 has an upwardly projecting portion 15 of smaller diameter to which are secured at inlet fitting 16 and a pair of discharge tubes 17 that terminate in a pivoted nozzle 18. The atomizer 10 is of a conventional type readily available on the market and widely used by dentists and physicians. The liquid such as a medicament to be sprayed is placed in

2

the reservoir 11. Conventionally, the user clips an air hose to the fitting 16. The flange 20 is used as part of the mechanism for holding the air hose and the atomizer together and the air hose is provided with a tapered member adapted to make a connection within the tapered bore 21 of the fitting 16. The air hose has a valve at its end so that the user can, with one hand, position and direct the atomizer and control the discharge of spray from it.

The present invention provides means whereby similar convenience of operation and effectiveness can be obtained without the necessity for a supply of compressed air. This is accomplished by means of an adapter indicated in general at 22 that is arranged to support the atomizer 10, the adapter in turn being detachably supported by a can or container 24 containing a liquified gaseous propellant. As appears below, the adapter provides a secure support for the atomizer 10, a conduit for conducting propellant gas from the can 24 to the atomizer and a convenient control for the valve that controls the discharge of gas from the can.

The container or can 24 is of a type widely used for dispensing aerosol products and comprises a cylindrical body 25 to which a concave bottom 26 is secured as shown in FIGURE 1, there being a small bead or flange 27 at the juncture of the cylindrical body 25 and the bottom 26. The can may be supported upon a base or stand 28 having flanges 29 on opposite sides and at the back thereof and a forwardly projecting portion 30. The flanges 29 engage the flange 27 on the bottom of the can and the projecting portion 30 prevents the assembly of atomizer, adapter and can from being overbalanced by the weight of the adapter and atomizer. The base readily slides onto or off of the can.

In order to provide a closure for can 24, the upper end of the can body 25 merges into a conical portion 32 that terminates in a short cylindrical portion 33 of less diameter than the body of the can and to which a closure member 34 is crimped. The closure member has a depressed central portion 35 in the center of which there is secured an upwardly projecting valve body 37 which contains a valve mechanism for controlling the discharge of fluid from the can. The valve may take any convenient form and preferably embodies a shoulder 38 and an upwardly extending discharge member 39 having a discharge passage 40 therein. The valve is actuated by a pin 41 that extends through the discharge passage 40 into the body of the valve. Depression of the actuating pin 41 opens the valve; releasing the actuating pin permits the valve to be closed by the action of a spring within the valve mechanism. The can is filled with liquified gas such as dichlorodifluoromethane or other appropriate halo-carbon, hydrocarbon or combination of gases having the desired temperature and pressure characteristics and which can be used with safety to spray medicaments and like materials. The container and the valve are preferably of well-known constructions and per se form no part of the present invention.

The adapter 22 is formed to be securely supported by the can 24 and in turn securely to support the atomizer 10, and to accomplish these functions merely by frictional and resilient engagement with the parts so that the adapter can be easily joined to or separated from either the atomizer, the can or both without requiring any tools or undue force. These results preferably are obtained by molding the body 45 of the adapter in one piece from a suitable, somewhat flexible plastic such as a polyethylene composition and providing the adapter with a cavity 46 to receive the can 24 and arms or forks 47 to engage the portion 12 of the atomizer, support the atomizer and maintain the required connection with the fitting 16. The adapter also has an intermediate portion 48 having a

raised portion containing a passageway or conduit 49 for conducting propellant gas from the valve discharge passageway 40 to the connection 16 of the atomizer. Passageway 49 terminates in a tapered nozzle 50 that fits within the tapered bore 21 of the inlet fitting 16 of the atomizer 10. The passageway 49 constitutes an expansion chamber for the propellant gas, and preferably, the flow of gas is metered by an orifice 51 that is formed in a flanged metal insert that is pressed into the passageway.

In order to detachably yet firmly support the adapter 22 on the can 24, the body 45 is provided with a lower, substantially cylindrical portion 52 having internally extending ribs 53 that make frictional engagement with the upper part of the body 25 of the can 24. The cylindrical portion 52 merges into a conical portion 54 that overlies the conical portion 32 of the can 24. The conical portion terminates in an upper, substantially cylindrical portion 55 that surrounds the crimped portion of the closure member 34 of the can 24. There is a flat circular surface 56 that extends inwardly from the cylindrical portion 55. This carries a downwardly projecting boss 57 having a recess 58 that closely engages the outer surface of the valve body 37. Recess 58 ends in a conical shoulder 59 from which a discharge bore 60 extends upwardly to intersect and go beyond the horizontal discharge conduit 49. Bore 60 snugly engages the discharge member 39 of the valve so that leakage of gas downwardly around the discharge member is substantially prevented.

The top wall 61 of the bore 60 is pierced to receive the actuating pin 41 that is closely engaged by the material of the wall so that the pin remains in place when the adapter is removed from a propellant can and also to prevent any substantial leakage of gas around the pin when the valve is opened. The pin 41 extends into a notched opening 63 in the projecting top 64 of the adapter. The notch 63 makes the top 64 into what is in effect a hinged flap, second class lever so that the user may without difficulty press the top downwardly into engagement with the pin 41 and thus open the valve. Gas then flows out of the discharge passageway 40 and into the horizontal passageway 49 through the metering orifice 51 to the atomizer. When the flap is released, the valve mechanism automatically closes by reason of a spring within the valve mechanism and also the vapor pressure of the fluid within the can.

The adapter is assembled with the can merely by pushing it onto the can with the center of the opening 46 substantially aligned with the axis of the can. The inner surfaces of the ribs 53 define a diameter slightly less than the diameter of the can body 25 so that secure frictional engagement is obtained between the can and the adapter. The flexibility of the plastic material from which the adapter is molded enables it to make proper frictional engagement with propellant cans even though the cans may be slightly out of round or of varying diameter, within ordinary commercial tolerances. The adapter is properly located with respect to the can by engagement between the bottom end of the downwardly projecting boss 57 and the surface of the closure member 35 immediately surrounding the valve body 37 or by engagement of the shoulder 59 and the shoulder 38 of the valved body. The adapter is removed from the can simply by pulling it off of the can, the pin 41 being frictionally retained in the top wall 61 as mentioned above.

The atomizer 10 is supported by opposed arms 47 that extend from the body 45 of the adapter and are integral with the remainder of the adapter. The arms 47 are shaped resiliently to embrace the metal body 12 of the atomizer and urge it toward the body of the adapter. Preferably the adapter is separated from the atomizer, the space between the arms is a little less than that required by the body portion 12 of the atomizer. Also, the centers of the arcs defining the inner surfaces of the arms are offset toward the body of the adapter from the axis of the atomizer when the atomizer is engaged by the arms.

The result is that when the atomizer is in position as shown in FIGURE 2, the arms 47 resiliently embrace the body 12 with sufficient force to hold the atomizer firmly in position. In particular, the arms engage the body 12 in the zones 66 and are spaced from the body 12 in the zones 66a with the result that the resilience of the arms tends to urge the atomizer toward the body of the adapter when the atomizer is pushed into place between the arms and with the fitting 16 of the atomizer engaging the nozzle 50 of the adapter. This action maintains the required fluid-tight connection between the nozzle and the fitting while the engagement between the nozzle and the fitting prevents vertical displacement of the atomizer with respect to the adapter. Thus the nozzle cooperates with the arms to correctly support the atomizer, while the arms cooperate with the nozzle in maintaining the required fluid connection between the atomizer and the adapter.

The outer surface of the arms 47 are sloped downwardly as shown at 67 so that the adapter will not interfere with the vision of the user of the atomizer and the ends of the arms are rounded as at 68 to facilitate insertion of the atomizer into the space between them. The lower portions of the arms are cut away as shown at 69 to receive the glass bottle 11, and this arcuate portion of the adapter is provided with a projecting lug 70 that engages the bottle as shown in FIGURE 3 to balance the forces on the atomizer and maintain it in a position substantially parallel to the axis of the can when the can, atomizer and the adapter are assembled. The lug preferably is made resilient by the provision of a slit 70a; the resilience of the lug enables the adapter to variations in diameter, eccentricity and out of roundness of the container, within ordinary commercial tolerances. The recesses 71, 72 and 73 in the adapter are simply for convenience in molding and to reduce the amount of plastic required.

In operation, the user simply places the adapter on a propellant can, pushing it down as far as it will go, and then pushes the atomizer laterally into engagement with the arms 47 and with the nozzle 50 within the fitting 16 of the atomizer. The atomizer is operated by depressing the flap 64 to depress the pin 41 and open the valve so that the propellant gas is discharged through the atomizer. The user can easily depress the flap with his first finger while holding the can with his thumb and remaining fingers. Thus, the device can be operated readily with one hand. As soon as the flap 64 is released, the valve automatically closes and discharge of medicament or other material from the atomizer stops. Ordinarily, the adapter is left on a given can of propellant until the propellant is exhausted. One can of propellant and one adapter can be used with several different atomizers containing different materials to be sprayed, if desired, since it is a very simple matter to connect and disconnect the atomizers. The expansion chamber provided by the passageway 49 and the metering orifice 51 insure that the propellant gas is discharged at the proper rate and result in efficient usage of the gas. The device is simple, compact and light in weight and can be manufactured at reasonable cost. Since it can be operated by one hand, it gives the user all of the convenience of compressed air operated atomizers plus the ability to use the atomizer in any location.

Those skilled in the art will appreciate that various changes and modifications can be made in the invention without departing from the spirit and scope thereof. The essential characteristics of the invention are set forth in the appended claims.

We claim:

1. An adapter for connecting an atomizer to a container for a liquified propellant gas, said atomizer comprising a body having a fitting adapted for connection to a source of propellant gas, a discharge nozzle projecting from the body and a reservoir for liquid to be sprayed depending from the body, said container having a discharge opening and a valve for controlling the discharge

of gas therefrom; said adapter comprising a body portion adapted to be frictionally and detachably mounted on said container, said body portion of said adapter having a passageway adapted to communicate with the discharge opening of the container when said adapter is in place on said container, said adapter also comprising means for connecting said passageway to said fitting of said atomizer by straight-line movement of said atomizer with respect to said adapter and means for frictionally and detachably engaging said atomizer and supporting it with said fitting connected to said passageway.

2. An adapter for connecting an atomizer to a container for a liquified propellant gas, said atomizer comprising a cylindrical body having a fitting adapted for connection to a source of propellant gas, a discharge nozzle projecting from the body and a reservoir for liquid to be sprayed depending from the body, said container having a discharge opening and a valve for controlling the discharge of gas therefrom; said adapter comprising a molded plastic member having a body portion having a recess adapted to receive the upper portion of the container and to make frictional engagement therewith, said body portion of said adapter having a passageway adapted to communicate with the discharge opening of the container when said adapter is in place on said container, means carried by said adapter for operating said valve, means molded integrally with said body portion for connecting said passageway to said fitting of said atomizer and means molded integrally with and projecting from said body portion and adapted to frictionally and detachably engage the body of said atomizer and to support said atomizer with said fitting connected to said passageway.

3. An adapter according to claim 2 having a pair of oppositely disposed flexible arms extending from the body thereof and adapted to embrace the body of the atomizer and resiliently urge the atomizer toward the can of propellant gas.

4. An adapter according to claim 3 wherein the discharge passageway of the adapter terminates in a tapered nozzle that fits within a tapered bore of the atomizer fitting.

5. An adapter according to claim 4 wherein the arms are curved and urge the tapered nozzle of the adapter and the tapered bore of the atomizer fitting together.

6. An adapter according to claim 5 wherein said body portion has a lug disposed below the level of said arms and adapted to engage the liquid container of the atomizer to retain the atomizer in position with respect to the axis of the can when the adapter nozzle is in position within the fitting of the atomizer.

7. An adapter according to claim 6 wherein the lug is resilient.

8. An adapter according to claim 4 in which the discharge passageway in the adapter is provided with a metering orifice adjacent the nozzle.

9. In combination, a container for a liquified propellant gas, said container having a discharge opening and a valve for controlling the discharge of gas therefrom, an atomizer comprising a body having a fitting adapted for connection to a source of propellant gas, a discharge

nozzle projecting from the body and a reservoir for liquid to be sprayed depending from the body, and an adapter for supporting said atomizer from said container and conducting gas from said container to said atomizer, said adapter being formed separately from said container and said atomizer and comprising a body portion frictionally and detachably engaging the container, said body portion of said adapter having a passageway in communication with said discharge opening when said adapter is in place on said container, said adapter having means for operating said valve, means for connecting said passageway to said fitting and means for frictionally engaging said atomizer and detachably supporting it with said fitting connected to said passageway.

10. In combination, a container for a liquified propellant gas, said container having a discharge opening and a valve for controlling the discharge of gas therefrom, an atomizer comprising a body having a fitting adapted for connection to a source of propellant gas, a discharge nozzle projecting from the body and a reservoir for liquid to be sprayed depending from the body, and an adapter for supporting said atomizer from said container and conducting gas from said container to said atomizer, said adapter being formed separately from said container and said atomizer and comprising a one-piece molded plastic body portion having a recess frictionally and detachably engaging the upper portion of said container, said body portion of said adapter having a passageway in communication with said discharge opening when said adapter is in place on said container, said adapter having means for operating said valve, means for connecting said passageway to said fitting and means comprising a pair of opposed arms molded integrally with said body portion for frictionally and detachably engaging said atomizer and supporting it with said fitting connected to said passageway.

11. Apparatus according to claim 10 wherein the discharge valve in the container has a cylindrical discharge member extending vertically upwardly from the container and the adapter is provided with a recess that closely engages said discharge member, the recess in the adapter communicating with the adapter discharge passageway.

12. Apparatus according to claim 11 wherein the adapter embodies a pin adapted to open the discharge valve of the container, the adapter having a hinged flap for engagement with said pin.
